UNITED STATES PATENT OFFICE.

CHARLES L. BETTS, OF BROOKLYN, NEW YORK, ASSIGNOR TO R. E. DIETZ COMPANY, OF NEW YORK, N. Y.

VEHICLE-LAMP.

SPECIFICATION forming part of Letters Patent No. 744,952, dated November 24, 1903.

Application filed August 13, 1902. Serial No. 119,523. (No model.)

To all whom it may concern:

Be it known that I, CHARLES L. BETTS, a citizen of the United States, and a resident of New York, in the borough of Brooklyn, county 5 of Kings, and State of New York, have invented a new and useful Improvement in Vehicle-Lamps, of which the following is a specification.

This invention relates to that class of vehicle lamps or lanterns in which the oil-pot is removably arranged in the lower portion of the lamp frame or body, into which the oil-pot is inserted from below and in which the oil-pot is supported by projecting parts and locked against turning by a spring-catch. Heretofore these fastening devices have been of such a nature that the part with which the spring-catch engages was concealed within the lamp or body frame, so that it was impossible to determine by sight whether the oil-pot had been turned sufficiently to interlock the spring-catch with the part with which it engages. It therefore often happened that the oil-pot was inadvertently left unlocked, in which case the oil-pot was liable to work back by the jarring of the vehicle until the supporting-parts cleared each other, when the oil-pot dropped out.

The object of this invention is to construct the spring-catch and the part with which it engages in such manner that these devices are exposed to view, so that it can be readily determined whether or not the oil-pot has been securely locked in position.

In the accompanying drawings, consisting of two sheets, Figure 1 is a sectional elevation of the lower portion of a lamp or lantern provided with my improvement and showing the oil-pot locked by the spring-catch. Fig. 2 is a horizontal section in line 2-2, Fig. 1. Fig. 3 is a perspective view of the notched supporting-ring on the inner side of the bottom ring of the lamp frame or body. Fig. 4 is an elevation of the lower portion of the lamp or lantern, showing the oil-pot unlocked.

Like letters of reference refer to like parts in the several figures.

A represents the bottom or base ring of the frame or body of a vehicle lamp or lantern, and B the removable oil-pot. The lower end of the bottom ring is preferably flared out-

wardly to provide a socket c, and in this socket is secured a supporting-ring D, which has an outer vertical flange d, an inner vertical flange d', and a bottom d'', connecting the 55 lower edges of said flanges. The ring is firmly secured in the socket against an internal shoulder thereon by turning inwardly the lower edge of the socket or in any other suitable manner. The upper portion of the 60 oil-pot is reduced to provide a neck E, which is adapted to be inserted into the supporting-ring and at the base of the neck with an annular horizontal shoulder f, which extends outwardly beneath the bottom-ring socket 65 and on which the latter rests.

G represents radial studs, preferably four, projecting outwardly from the neck of the oil-pot and arranged equidistant around the neck. The supporting-ring D is provided in 70 its bottom and inner walls with notches g, and the inner flange of the ring is reduced adjacent to each notch to provide a slightly-inclined lateral shoulder g' and an upright stop-shoulder g'' at the end of the lateral 75 shoulder. In inserting the oil-pot in the frame the studs G pass upwardly through the notches g in the ring. The pot is then partially turned, so that the studs ride upon the inclined shoulders g' and draw the pot tightly 80 into the socket. The stop-shoulders limit the turning movement of the oil-pot. One of the notches g in the supporting-ring (that at the left in Figs. 1 and 2) is enlarged sufficiently 85 to permit the passage of the knob on the end of the wick-raiser shaft, and the flaring portion of the bottom ring is provided with an opening h for the same purpose. Any other suitable construction of the parts which support the oil-pot may, however, be employed. 90

I represents the spring-catch or locking-lever for holding the oil-pot from turning in the frame. This lever is arranged on the outside of the oil-pot in a substantially upright position, so that its lower end or thumb-piece can 95 be conveniently pressed inwardly by the thumb when a person grasps the oil-pot to remove it from the frame. The lever is provided at its upper end with an inwardly-extending tooth or projection i, which stands 100 opposite the lower portion of the bottom ring when the oil-pot has been inserted into the

same and is adapted to spring into an opening or recess *j* in the bottom ring when the lever is brought opposite this opening by turning the oil-pot in the frame. In the construction shown the locking-lever is pivoted for convenience in assembling the parts on a plate *i*', which is soldered to the oil-pot, and its upper end is pressed inwardly by a spring *i*², coiled about the pivot-pin and having one end bearing against the lever and the other against the pivot-plate. The tooth *i* on the lever is preferably curved or inclined, so that the oil-pot can be pushed up into the frame without operating the lever by hand.

15 When the oil-pot is inserted into the bottom ring, the locking opening or recess *j* in the latter is exposed to view on one side of the locking-lever, as represented in Fig. 4. The oil-pot carrying the locking-lever is then turned until the latter engages in the opening *j*, and the fact that the lever has been securely engaged in the opening is readily ascertained, as the opening is externally arranged and visible as well as the lever or catch. In the fastenings now generally used in lamps of this character the spring-catch is arranged on the bottom ring of the lamp-body, and the depression or recess in which the catch engages is arranged on the upper part 30 of the oil-pot. When the latter is inserted in the bottom ring, the locking depression or recess is concealed by the bottom ring, and the fact that the parts have been interlocked is ascertained mainly by sound, which method 35 is unreliable. The consequence is that the parts are often left unlocked, in which case the oil-pot is liable to drop out. This is particularly objectionable in lamps which are used on road-vehicles, where the dropping 40 out of the oil-pot usually results in its loss.

Another advantage of this construction is that it renders the manipulation of the oil-pot very convenient, as the thumb of the hand

which grasps the oil-pot is placed on the catch for releasing the latter and the hand is not required to change position with reference to the oil-pot in turning the latter back after the catch has been released. Furthermore, as the parts of the fastening are in plain view the operation of the same is readily ascertained and understood by persons who have no experience with lamps of this character.

I claim as my invention—

1. The combination of a lamp-body having its lower portion provided with an external locking-recess, an oil-pot adapted to be inserted into said body from below and to be turned therein, means on said body and oil-pot for supporting the latter on said body, and a spring-catch attached to said oil-pot 55 and engaging the locking-recess of the body when the oil-pot has been turned the required distance, whereby said locking-recess is exposed to view on one side of the spring-catch when the oil-pot is unlocked, substantially as 60 set forth.

2. The combination of a lamp-body having its lower portion provided with an external locking-recess, an oil-pot adapted to be inserted into said body from below and to be turned therein, means on said body and oil-pot for supporting the latter on said body, and a spring-locking lever pivoted in an upright position on said oil-pot and engaging with its upper end in the locking-recess of 75 the body when the oil-pot has been turned the required distance and having its lower end adapted to be pressed inwardly for releasing the lever from said recess, substantially as set forth.

Witness my hand this 11th day of August, 1902.

CHARLES L. BETTS.
